Primary Examiner — Mary Ann Calabrese*Assistant Examiner* — Hillary Catherine Shepard(74) Attorney, Agent, or Firm — Egbert, McDaniel & Swartz, PLLC(57) CLAIM

The ornamental design for a table as shown and described.

DESCRIPTION

FIG. 1 is a rear perspective view of a table showing my new design.

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view thereof.

The broken lines shown in the drawings illustrate portions of the table that form no part of the claimed design.
